JOHN E. SMITH, OF WATERBURY, CONNECTICUT.

Design No. 4,426, dated October 18, 1870.

DESIGN FOR A BUCKLE.

The Schedule referred to in these Letters Patent and making part of the same

To whom it may concern:

Be it known that I, JOHN E. SMITH, of Waterbury, in the county of New Haven and State of Connecticut, have invented a new Design for Buckle; and I do hereby declare the following, when taken in connection with the accompanying drawing and the letters of reference marked thereon, to be a full, clear, and exact description of the same, and which said drawing constitutes part of this specification, and represents a front view of a buckle, in which is embraced my new design.

This invention relates to a design or ornament for suspender-buckles, and it consists in a ring or band upon the buckle-plate, surrounded by ornamentation conforming to the said band, the object of the said

band being a frame for the insertion of a portrait or other picture.

Upon the face or plate of the buckle I form a ring or band, *a*, the plate being ornamented to correspond to the band or ring, the said band being employed for the insertion of a portrait; but I do not wish to be understood as making the portrait any part of this invention.

I claim as my invention—

The design for ornamentation of suspender-buckles, as shown and described.

JOHN E. SMITH.
